UNITED STATES PATENT OFFICE.

THOMAS BOVEY, OF CHICAGO, ILLINOIS.

CASING FOR AUTOMOBILE HEATERS.

Application filed March 22, 1923, Serial No. 626,933. Renewed September 15, 1926.

My invention relates to the construction of the casing of automobile heaters which derive their heat from the exhaust of the engine (not shown), by means of elbows extending up through the ends of the bottom thereof, into a radiator contained therein.

The objects of my invention are to provide doors in the bottom of the casing that can be easily opened or closed from above and through which the dirt and dust falling therein can be discharged when said doors are opened, substantially as hereinafter fully described and as illustrated in the claims.

In the drawings:

Figure 1 is a plan view of the underside of the casing of the heater.

Figure 2 is a transverse section of the same, taken on dotted lines 2, 2, Figure 1, showing the doors in the bottom thereof closed.

Figure 3 is a longitudinal section of the casing.

Figure 4 is a view similar to Figure 2 with the doors shown in open position.

In the drawings the casing is shown to be pan-shaped and consists of a flat outwardly flanged rim 10, side walls 11, depending downwards and inwards therefrom, and a bottom 12 that inclines at the sides and ends toward two rectangular openings or doorways 13, 13, located on each side of the transverse center of the casing.

These openings or doorways 13, 13, as shown in the drawings, are preferably, longer than they are wide, and they are closed by doors or traps, 14, 14, whose inner edges are provided with suitably spaced knuckles 15 which connect with the knuckles 16, 16, made integral with the inner longitudinal edges or margins of the doorways.

The bottom of the casing between the doorways is provided with an upwardly projecting longitudinal rib 17, that inclines towards the ends and sides thereof, and disappears in about the transverse plane of the ends of the doorways. The rib reinforces the bottom of the casing and provides a seat for the cross bar as hereinafter described.

The bottom in alignment with the ends of the rib is flattened, and in this flattened area are openings 18, 18, down through which the receiving-stub 18^a of the radiator at one end of the casing and the discharge-stub at the other end thereof, (not shown), depends downwards from the radiator 19.

The longitudinal rib 17 has its sides in-

clined toward the doorways and at its center of length it is provided with a hole 20 for the passage of the shaft or stem 21, whose upper end is rotatable within a boss 22, depending from the center of the underside of the perforated cover plate 23. This shaft or stem extends down below the hole 20 and has a cross-bar 24 pivoted thereto at its center of length. The arms of this cross-bar, when it is in a lateral position extend to and slightly beyond the center of width of doors 14, 14, and keep them closed. Said stem or shaft has a cotter-pin 25 at a suitable point between the bottom of the casing and the perforated cover-plate 23. A washer 26 is placed immediately below this cotter-pin and between this washer 26, and top of the rib 17, a coil extension-spring 27 surrounds the shaft or stem 21, and keeps said shaft or stem and cross-bar always pressing upward.

Ordinarily said cross-bar 24 is in a transverse position, substantially as shown in Figure 2 of the drawings, and when it is desired to open said doors the stem is turned laterally by inserting a screw-driver in the slot 28 in its upper exposed end, and given a quarter turn. This places the cross-bar in a longitudinal position in the concave portion of the reinforcing rib 17, and permits the doors to drop, substantially as shown in Figure 4.

The cross-bar is pivotally connected to the shaft or stem to equalize upward pressure on the doors even if parts are in slight misalignment.

What I claim as new:

1. A casing for an automobile heater which is pan-shaped and has a doorway in its bottom, upon each side of its center of width, a door hinged to the inner longitudinal side of each doorway, and means operable from above said casing for closing and permitting said doors to open.

2. A casing for an automobile heater which is pan-shaped and has a doorway in its bottom on each side of the center, doors hinged to the inner sides of said doorways, and vertically disposed yielding means operable from above said casing for closing and opening said doors.

3. A casing for an automobile heater which is pan-shaped and has a doorway in its bottom, on each side of its center of width, doors hinged to the inner sides of said doorways, a vertical shaft or stem adapted to be given a quarter turn extending between said

doorways and arms secured to and projecting in opposite directions from the lower end of said shaft or stem which latter is operable from above said casing for opening and closing said doors.

4. A casing for an automobile heater which is pan-shaped and has doorway in its bottom, the bottom between the longitudinal sides of said doorway having a longitudinal rib, doors hinged to the edges of said doorway, a vertical disposed shaft or stem having a slot in its upper end, said stem extending from the top of the case down through the rib, a cross-bar secured to the lower end of said stem, and a spring engaging said shaft or stem and keeping it normally at the upper end of its movement.

5. A casing for an automobile heater which is pan-shaped and has a doorway in its bottom, a door hinged to one of the edges of said doorway, a rotatable stem extending from adjacent said door to the top of the casing, and means operatively connecting said door and stem whereby the opening and closing of said door is controlled.

6. In automobile heaters, a casing having an open bottom, a heat radiating element therein, hinged means for opening and closing the casing bottom, a grating on the casing and a central operating stem terminating in and accessible from above the grating adapted to control the opening and closing means.

7. A container for an automobile heater comprising a casing and cover therefor, said casing provided with a plurality of clean-out openings in its bottom, doors for opening and closing said clean-out openings, and means accessible through the cover for controlling the operation of said doors.

8. A container for an automobile heater comprising a casing and cover therefor, said casing provided with a pair of side by side clean-out openings in its bottom, doors hinged to the edges of said openings for opening the same; and means accessible through the cover for controlling the operation of said doors.

9. A container for an automobile heater comprising a casing and cover therefor, said casing provided with a plurality of clean-out openings in its bottom, reinforcing means between said openings, and closures for said openings.

10. A container for an automobile heater comprising a casing and a cover therefor, said casing provided with a plurality of clean-out openings in its bottom, doors for opening and closing said cleanout openings, and a stem operatively connected to said doors and extended to said cover for controlling the operation of said doors.

11. A container for an automobile heater comprising a casing and cover therefor, said casing provided with a plurality of clean-out openings in its bottom, doors for opening and closing said clean-out openings, a stem rotatably mounted in said cover, and means operatively connecting said stem to said doors whereby to control the opening and closing of the latter.

12. A container for an automobile heater comprising a casing and cover therefor, said casing provided with a plurality of clean-out openings in its bottom, doors for opening and closing said clean-out openings, a rotatable stem accessible from above said cover and means connected with said stem and operable by the rotation thereof for controlling the opening and closing of said doors.

13. A container for an automobile heater comprising a casing and cover therefor, said casing provided with a plurality of clean-out openings in its bottom, doors for opening and closing said clean-out openings, and means attached to said doors and extending to the cover and accessible therethrough for controlling the operation of said doors.

14. A container for an automobile heater comprising a casing and cover therefor, said casing provided with a clean-out opening in its bottom, a door movable to open and close said opening, and means attached to said door and extending to the cover and accessible therethrough for operating said door.

15. In a heater of the class described, a casing having an aperture in the bottom thereof, a radiator within the casing, a grate spanning the casing above the radiator, a door for closing the aperture therein, and an upwardly spring-pressed plunger disposed substantially flush with the grate at a point in the center thereof above the door for operating the same to open the aperture.

In witness whereof, I set my hand this 12th day March, 1923.

THOMAS BOVEY.
